(57) **CLAIM**

The ornamental design for a peripheral device for computers, as shown and described.

DESCRIPTION

FIG. 1 is an upper perspective view of a first embodiment of our design;

FIG. 2 is a rear elevation view thereof;

FIG. 3 is a bottom plan view thereof;

FIG. 4 is a front elevation view thereof;

FIG. 5 is a left side elevational view of the body of the device, the right side being a mirror image thereof; the left elevational view of the cable is shown, the right side elevational view is a mirror image of the left side; and,

FIG. 6 is top plan view thereof.
